FIG. 7

FIG. 1 is a side elevational view of a hand lantern showing one embodiment of our new design with the headlamp and handle both shown tilted upwardly about their pivotal connection to the frontal standard.

FIG. 2 is a front elevational view of the embodiment shown in FIG. 1, with the headlamp and handle both shown in a horizontal position.

FIG. 3 is a rear elevational view of the hand lantern as shown in FIG. 2.

FIG. 4 is a perspective view of the hand lantern as shown in FIG. 2.

FIG. 5 is a side elevational view of a hand lantern showing another embodiment of our new design shown in FIG. 1, with the headlamp and handle both shown tilted upwardly about their pivotal connection to the frontal standard.

FIG. 6 is a front elevational view of the embodiment shown in FIG. 5, with the headlamp and handle both shown in a horizontal position.

FIG. 7 is a rear elevational view of the hand lantern as shown in FIG. 6.

FIG. 8 is a perspective view of the hand lantern as shown in FIG. 6.

The side of the hand lantern not shown is substantially the same in appearance as the side shown.

This application is a continuation of our copending applications Serial Nos. D. 57,004 and D. 57,005, both filed on July 30, 1953 and now abandoned.

We claim:

The ornamental design for a hand lantern, as shown and described.
